Security Aluminum Corporation, Compton, Calif., a
corporation of California

Filed Aug. 12, 1963, Ser. No. 76,179

Term of patent 14 years

(Cl. D10—8)

FIGURE 1 is a perspective view of a handle embodying my new design, an associated sash frame being shown fragmentarily in phantom lines for purpose of illustration and the handle of my new design being shown in one of its two pivotal positions with respect thereto;

FIGURE 2 is a rear elevational view of the handle shown in FIGURE 1;

FIGURE 3 is a right-side elevational view of the handle shown in FIGURE 2;

FIGURE 4 is a bottom plan view of the handle shown in FIGURE 2;

FIGURE 5 is a front elevational view of another embodiment of a handle employing my new design and having a decorative pattern embossed thereon;

FIGURE 6 is a sectional view taken along the line 6—6 in FIGURE 5;

FIGURE 7 is a front elevational view of still another embodiment of a handle employing my new design and having a decorative array of apertures therein; and

FIGURE 8 is a sectional view taken along the line 8—8 of FIGURE 7.

I claim:

The ornamental design for a handle, as shown and described.
